(57) **CLAIM**

The ornamental design for a stand for monitor, as shown and described.

DESCRIPTION

FIG. 1 is a front, top, and right side perspective view of a stand for monitor;

FIG. 2 is a rear, top, and left side perspective view thereof;

FIG. 3 is a front elevational view thereof;

FIG. 4 is a rear elevational view thereof;

FIG. 5 is a top plan view thereof;

FIG. 6 is a bottom plan view thereof; and,

FIG. 7 is a right side elevational view thereof, the left side elevational view being a mirror image of the right side elevational view.

The evenly spaced broken lines shown in the figures are for the purpose of illustrating portions of the stand for a monitor that form no part of the claimed design. The dot-dash broken lines at the bottom of the claimed design show a boundary between the claimed portion of the stand for a monitor and the unclaimed portion thereof.

1 Claim, 6 Drawing Sheets
